UNITED STATES PATENT OFFICE.

CARTER H. PAGE, JR., AND ERNEST L. BRUNDRETT, OF PHILADELPHIA,
PENNSYLVANIA.

DESIGN FOR A SHADE-SUPPORT.

SPECIFICATION forming part of Design No. 28,470, dated April 12, 1898.

Application filed March 29, 1897. Serial No. 629,862. Term of patent 14 years.

To all whom it may concern:

Be it known that we, CARTER H. PAGE, Jr., and ERNEST L. BRUNDRETT, citizens of the United States, residing at the city of Philadelphia, in the county of Philadelphia and State of Pennsylvania, have invented and produced a new and original Design for a Shade-Support, of which the following is a specification, reference being had to the accompanying drawing, forming part thereof, and in which a shade-support embodying the shape constituting our design is illustrated in perspective.

The leading feature of our design consists in the shape shown in the drawing, and it may be said to comprise a perforated disk, a ring-like band flanged at its periphery, and

curved arms extending upward from the band to the edge of the disk.

In the drawing, *a* is the ring-like band, upwardly flanged, as at *b*. *A* is the centrally-perforated disk, and *c* are the curved arms that extend upward from the ring-like band *a* to the periphery of the disk *A*.

What we claim is—

The design for a shade-support, substantially as shown and described.

In testimony whereof we have hereunto signed our names.

CARTER H. PAGE, JR.

ERNEST L. BRUNDRETT.

In presence of—

F. H. MACMORRIS,
THOS. A. JAMES.
